MEANS FOR DRAWING OFF BLAST FURNACE
GASES BY SUCTION IN ROASTING, CAL-
CINING, AND DRYING FURNACES

Josef Horak, Eisenerz, Germany

Application February 4, 1939, Serial No. 254,735
In Austria February 19, 1938

2 Claims. (CL. 263—29)

In order to enable the material that is to be charged, in roasting and calcining furnaces that require an open top, to be brought in and distributed without being hindered by waste gases and dust, according to this invention a suction grate is arranged immediately underneath the open top of the furnace. This suction grate consists of hollow bearers, which are located side by side with spaces between them, and which are provided with suction apertures, with their open ends opening into suction passages leading to a ventilator or to the chimney stack or the like. This renders unnecessary the known super-structures upon the top of the furnace shaft, such as the usual hoods or bonnets or other closures.

Two embodiments of the apparatus according to the invention are illustrated by way of example in the accompanying drawing, in which

Figures 1 to 3 represent a rectangular shaft furnace, and

Figures 4 to 6 a round shaft furnace, without and with dust-removing nozzles.

Figures 1, 4 and 7 are sectional elevations taken transversely through the hollow grate-bar bearers;

Figures 2 and 5 are sectional elevations parallel to the hollow grate-bar bearers, and Figures 3 and 6 are plan views.

Transversely above the furnace shaft at distances that are determined according to the size of grain of the material to be treated run tubular hollow grate-bar bearers 1. The charge need only reach up to the upper edge of the suction grate, in the case of an ordinary size of grain, in order to prevent the suction of secondary air through the suction apertures 2 provided on the under side of the hollow grate-bar bearers 1.

In order to enable as many hollow grate-bar bearers 1 as possible to be located in the cross section of the furnace, and to prevent any appreciable segregation of the charge, the hollow grate-bar bearers 1 are made narrow, and preferably exhibit a rectangular cross section standing on edge, which is saddle-shaped at the top.

The open ends of the hollow grate-bar bearers 1 open according to Figures 1, 2 and 3 into a suction duct 4, preferably enclosing the entire cross section of the furnace. Upon this suction passage is mounted the connection 5 to a ventilator. The waste blast-furnace gases drawn off by any suction apparatus are blown out into the atmosphere at a height which is no longer troublesome, or may be strained or otherwise employed. The suction passage 4, built along with the suction grate, and provided with cleaning apertures, is mounted upon the masonry 6 of the chimney stack.

Figures 4 to 6 illustrate an annular suction

passage 7, which increases in depth from the mouths of the middle hollow grate-bar bearer on both sides towards the mouths of the outermost hollow grate-bar bearers, and upon the inclined sole of which the dust is precipitated to two diametrically opposite suction connections 8. These connections or nozzles 8 may also be shut off, and in this case the suction is effected through one or two opposite suction nozzles 8'.

Figure 7 shows hollows grate-bar bearers with lateral suction apertures 2', which have to be covered over unless they are smaller than the size of grain of the charge.

The hollow grate-bar bearers, if a relatively stiff and fire-proof structural material is employed, such as sheet steel, cast steel, cast iron or artificial stone, may be open on the under side throughout their length.

The apparatus according to the invention is distinguished by great simplicity, small over-all height, and therefore ease of insertion, the open top of the furnace shaft remaining completely free. The apparatus composed of the hollow grate-bar bearers, suction passages, dust-removing connections and ventilator connections can be mounted upon the masonry of the shaft or can be inserted in the frame structure or masonry of the shaft at any convenient height, even below the open top of the furnace shaft.

What I claim is:

1. Means for drawing off waste blast-furnace gases by suction in shaft furnaces having open tops for roasting, calcining or drying, comprising a suction grate fitted into the furnace immediately below the open top of the furnace, the said suction grate consisting of tubular hollow bearers formed with suction apertures, and the ends of the hollow bearers being open, and a channel of large cross section surrounding the stack and in communication with the open ends of the hollow bearers for producing an equalization of pressure on the entire circumference of the furnace.

2. Means for drawing off waste blast-furnace gases by suction in shaft furnaces having open tops for roasting, calcining or drying, comprising a suction grate fitted into the furnace immediately below the open top of the furnace, the said suction grate consisting of tubular hollow bearers, formed with suction apertures, and the ends of the hollow bearers being open, a ventilator, an annular channel of large cross section surrounding the furnace and in communication with the open ends of the bearers, and a ventilator having a suction inlet connected with the channel.

JOSEF HORAK.
